WELDER'S ELECTRODE HOLDER

Clifford Laskey, Albany, Calif.

Application June 1, 1942, Serial No. 445,291

5 Claims. (Cl. 219—8)

This invention relates to welder's electrode holders of the type adapted to be connected to a source of electrical energy and be transported manually from one work assignment to another.

It is an object of this invention to provide a completely insulated electrode holder furnishing the utmost in safety for the operators and precluding any possibility of damage or injury to work surfaces or the holder itself when intentionally or otherwise dropped or laid on the surface of grounded metal.

It is a further object of this invention to provide a welder's electrode holder which, in addition to the above enumerated advantages, will be relatively inexpensive to manufacture and convenient to operate. It is a further object of the invention to provide an electrode holder of such simple construction that it may be readily disassembled for inspection, maintenance and repair and replacement of parts.

These and other objects of the invention will become more apparent as this specification proceeds and the particular novelty of the device will be defined in the appended claims.

In the drawings forming a part hereof,

Figure 1 is a side elevation of the device forming the subject matter hereof,

Figure 2 is another side elevation of the device with the parts thereof in slightly different position,

Figure 3 is a vertical sectional view taken along the line 3—3 of Figure 1, and

Figure 4 is another sectional view taken along the line 4—4 of Figure 1.

The electrode holder forming the subject matter of this application was designed primarily, though by no means exclusively, for use in shipbuilding. It is well known that in shipyards welding electrode holders are subjected to extremely rough usage and that as a consequence the repair and replacement costs are exceedingly high. It is also a well known fact that the holders most commonly used in this particular art are of the tong type wherein the electrodes are retained between spring jaws. As it is virtually impossible to fully insulate the tong type holders the exposed contact points are the cause of countless accidents in which the operator is injured, or the work surface damaged, or the holder itself is damaged or destroyed. For example, when any conducting part of the devices comes in contact with grounded metal the current will arc causing flashes or burning, the latter being extremely destructive in character.

The electrode holder forming the subject mat-

ter hereof overcomes the stated and other objections to the prior art devices in that it is a fully insulated structure.

Referring now to the drawings wherein there is illustrated a preferred embodiment of the invention, the numeral 10 designates an elongated conductor tube of copper, or other conducting material, encased within a cover 11 of insulating material, such as pressed paper fiber or the like. 5 As will be noted from Figures 3 and 4, the conductor tube 10 is open-ended and its upper end is enclosed by the cover 11. The cover 11 is rigidly secured on the conductor tube 10 by means of a pin 12 which is preferably, though not necessarily, of fiber or other suitable insulating material.

The conductor tube 10 is provided with complementary longitudinally extending slots 15 projecting downwardly from its upper end. The 10 insulating cover 11 likewise has a pair of complementary longitudinally extending slots 16, terminating short of its upper or closed end and in registry with a substantial portion of the slots 15 in tube 10. The registering portions of slots 15 15 and 16 provide clearance for pin 20, of fiber or other insulating material, connecting rod retaining plunger 21, slidably disposed within the tube 10, and sleeve 22 telescoped upon the upper portion of cover 11. It will thus be seen that 20 sleeve 22 and the rod retaining plunger 21 are coupled for unitary movement within the limits defined by the length of the slots 16 in cover 11, or by a welding rod 18 inserted into the device.

The device forming the subject matter of this 25 application will retain an electrode 18 in two separate and distinct positions, first, at right angles to the body of the structure and second, at an oblique angle (see Figure 3). This is made possible by the use of a tubular insert 25 secured 30 within the upper end of tube 10 by means of a pin 26. The insert 25 is provided with a pair of oppositely disposed openings 27 and 28, aligned with the upper ends of the slots 15 in tube 10 and an aperture 29 in cover 11, respectively, to 35 receive the welding rod 18 when disposed at right angles to the body of the structure. The lower edge of the insert 25, beneath the opening 27, is undercut, as at 30, to provide an opening to receive the inner end of an electrode 18 when disposed at an oblique angle to the body of the structure 40 (see Figure 3).

The rod retaining plunger 21 is normally urged 45 upwardly past the openings 27 and 28 in the tubular insert 25 and against the cross pin 26 by a coil spring 34. The upper end of the spring 34

is seated against the lower end of the plunger 21 in a cup or sleeve 35 of insulating material, of any well known type, fitted on the plunger, while the lower end of the spring 34 is seated in a cup 36 of insulating material anchored in the conductor tube 10 by means of a cross pin 37.

The lower end of the cover 11 is encased within a grip 39 secured adjacent its upper end by means of a fiber pin 40 extending through tube 10 and cover 11. As will be noted from Figures 1 and 2, the grip 39 is relieved at one side, as at 41, to facilitate movement of the holder with respect to a conventional electrical cable 42 with which it is adapted to be connected.

An improved means for connecting the conductor element 10 of the holder with the cable 42 is shown in Figures 3 and 4 as comprising obliquely disposed slots 43 cut into one side of tube 10 and terminating in a pair of medially disposed openings 44 adapted to receive a wedge pin 45. Having stripped an end of cable 42 of its conventional insulation to bare wires 46, the end of the cable is inserted in the lower end of tube 10 to dispose the mass of wires opposite and extending beyond the complementary openings 44. Wedge pin 45 is then driven into the slot 43 to obtain a connection between the cable and the tube sufficiently rigid for all normal operations, but also a connection which may be conveniently broken for inspection or repair of the holder by tapping out the wedge pin 45.

From the foregoing it will be seen that the construction and operation of the device is comparatively simple. In making the holder ready for use, the operator has merely to pull the sleeve 22 downwardly on cover 11, against the tension of the coil spring 34, to expose the opening 23 in cover 11, the elongated slots 16 in tube 10 and the complementary openings 28 and 27 in the insert 25, for insertion of the electrode 18.

If it be desired to place the electrode 18 at right angles to the body of the holder for normal welding operations, the rod 18 is inserted through opening 29 in cover 11, slot 15 in tube 10 and into the openings 28 and 27 in insert 25, with its inner end abutting cover 11. (See Figure 3.) By then releasing the sleeve 22 the tension of spring 34 will urge the plunger 21 upwardly in tube 10 against rod 18, at which point it will be held or gripped with sufficient rigidity for all normal welding operations. Additionally, sleeve 22 is notched, as at 23, to bear directly against and aid in proper positioning of rod 18.

If it be desired to dispose the rod 18 at an oblique angle to the body of the holder for overhead or close work, the sleeve 22 and the plunger 21 coupled therewith are simply moved downwardly to expose undercut 30 in insert 25. Rod 18 may be then inserted through the opening 29 in cover 11, slot 15 in tube 10, the opening 28 in insert 25, with its inner end below the undercut 30 in insert 25, and into slot 15 at the opposite side of tube 10 and abutting cover 11. Again, the tension of spring 34 will urge plunger 21 upwardly in tube 10 to hold the rod 18 in position. (See dotted lines in Figure 3.)

The burned down stubs of rods 18 may be quickly and conveniently removed from the holder by simply pulling downwardly on sleeve 22 and inverting the device permitting the stub to drop from the holder.

The breakdown of the device for inspection and repair is an extremely simple operation in that it is but necessary to tap out the fiber pin 20 to separate sleeve 22 from plunger 21 permitting

the former to be slipped from the cover 11. Grip 39 may be removed by simply tapping out pin 40 to separate it from the lower end of cover 11. Next, by removing pin 12, tube 10 is freed for removal from cover 11 and finally removal of pin 37 permits withdrawal of spring 34, the associated cup seat 36 and plunger 21.

An important feature of the present invention is the fact that except when a rod 18 is inserted 10 for normal operations, the device is fully insulated and provides a dead end for the cable 42 when the device is not in use. Thus it may be conveniently laid on any surface such as grounded metal or the like without the usual dangers thought to be a normal incident of the 15 use of electrode holders as a class.

From the foregoing it will be seen that I have provided a welder's electrode holder having many advantages and a high degree of utility in this 20 art. It will be understood that while I have shown and described herein a preferred embodiment of the invention, nevertheless, the principles thereof may take other forms and for this reason protection is desired according to the full 25 scope of the appended claims.

The invention claimed is:

1. A welder's electrode holder comprising, a tubular electrical conductor, a pair of complementary slots extending longitudinally of the tube 30 from one of its ends, an insulating cover for the tubular member, an electrode receiving opening in the cover in registry with one of the slots in the tubular member, said cover also having a pair of complementary slots spaced apart from one 35 of its ends in registry with a portion of the slots in the tubular member, an electrode engaging member slidably received in the tubular member, a spring seated in the tubular member normally urging the electrode engaging member past the 40 electrode receiving opening in said cover, a sleeve of insulating material slidably encasing a portion of said cover and having a non-conducting coupling through the slots in said cover and the tubular member with the slidable electrode 45 engaging member.

2. A welder's electrode holder comprising, a tubular electrical conductor, a pair of complementary slots extending longitudinally of the tube from one of its ends, an insulating cover for the 50 tubular member, an electrode receiving opening in the cover in registry with one of the slots in the tubular member, said cover also having a pair of complementary slots spaced apart from one of its ends in registry with a portion of the 55 slots in the tubular member, an electrode engaging member slidably received in the tubular member, a spring seated in the tubular member normally urging the electrode receiving opening in said cover, and means within the tubular member defining a two 60 position seat for the innermost end of the electrode inserted through the opening in said cover.

3. A welder's electrode holder comprising, a tubular electrical conductor, a pair of complementary slots extending longitudinally of the tube from one of its ends, an insulating cover for the 65 tubular member, an electrode receiving opening in the cover in registry with one of the slots in the tubular member, said cover also having a pair of complementary slots spaced apart from one of its ends in registry with a portion of the 70 slots in the tubular member, an electrode engaging member slidably received in the tubular member, a spring seated in the tubular member normally urging the electrode engaging member 75

past the electrode receiving opening in said cover, a sleeve of insulating material slidably encasing a portion of said cover and having a non-conducting coupling through the slots in said cover and said tubular member with the slidable electrode engaging member, and means within the tubular member defining a two position seat for the innermost end of the electrode inserted through the opening in said cover.

4. A welder's electrode holder comprising, a tubular electrical conductor, a pair of complementary slots extending longitudinally of the tube from one of its ends, an insulating cover for the tubular member, an electrode receiving opening in the cover in registry with one of the slots in the tubular member, said cover also having a pair of complementary slots spaced apart from one of its ends in registry with a portion of the slots in the tubular member, an electrode engaging member slidably received in the tubular member, a spring seated in the tubular member normally urging the electrode engaging member past the electrode receiving opening in said cover, a tubular insert in the tubular member having on one side an opening in registry with the opening in said cover and overlaying one of the slots in said

tubular member, and on its other side a pair of openings one of which complements the first mentioned opening.

5. A welder's electrode holder comprising, a tubular electrical conductor, a pair of complementary slots extending longitudinally of the tube from one of its ends, an insulating cover for the tubular member, an electrode receiving opening in the cover in registry with one of the slots in the tubular member, said cover also having a pair of complementary slots spaced apart from one of its ends in registry with a portion of the slots in the tubular member, an electrode engaging member slidably received in the tubular member, a spring seated in the tubular member normally urging the electrode engaging member past the electrode receiving opening in said cover, a sleeve of insulating material slidably encasing a portion of said cover and having a non-conducting coupling through the slots in said cover and the tubular member with the slidable electrode engaging member, a grip of insulating material encasing the end of the cover opposite that which receives the electrode.
